UNITED STATES PATENT OFFICE.

EDWARD E. BRIGHT, OF MORRIS, ILLINOIS, ASSIGNOR OF TWO-FIFTHS TO JOHN T. GEORGE, OF MORRIS, ILLINOIS.

LID-BRACKET FOR BOXES.

1,176,517.

Specification of Letters Patent. Patented Mar. 21, 1916.

Application filed December 19, 1914. Serial No. 878,175.

To all whom it may concern:

Be it known that I, EDWARD E. BRIGHT, a citizen of the United States, residing at Morris, in the county of Grundy and State of Illinois, have invented certain new and useful Improvements in Lid-Brackets for Boxes, of which the following is a specification.

The present invention has reference to certain new and useful improvements in brackets for supporting the lids of cigar boxes and the like when said lids are open, so as to display the contents of the box and present a neat appearance. At the same time the bracket or device to which the present application relates serves as a convenient support for a price tag or the like.

There have been devised in the past numbers of devices relating to the same general class to which the present device relates, but most of these are open to the objection that they are provided with arms or other extensions which must be forced down a considerable distance on the interior side of the box. By reason of this fact the cigars or other contents of the box are frequently injured during the application of the device. Furthermore, a device having the foregoing objection cannot be applied to an unusually shallow box.

The main object of the present invention is to provide a device of this class so constructed that it will clasp onto or take hold of the upper outside portion of the box and without the necessity of extending any portion of the device down any considerable distance into the interior of the box. This will permit the device to be applied to the box without disturbing the contents of the box, and, therefore, without danger of injuring the same. Another object is to provide a device of such construction that when it has once been applied it will very rigidly and securely hold the box lid at the desired angle, thereby overcoming an objection frequently found in devices of this general nature.

Other objects and uses will appear from a detailed description of the invention which consists in the features of construction and combinations of parts hereinafter described and claimed.

In the drawing: Figure 1 shows an outside view of the corner of a box and lid to which the device of the present invention has been

applied, a portion of the device being broken away; Fig. 2 is a section taken on the line 2—2 of Fig. 1, looking in the direction of the arrows; Fig. 3 is a view corresponding to Fig. 1, looking at the device from the interior of the box; and Fig. 4 is a perspective view of the device, which is illustrated in Figs. 1, 2, and 3, standing alone.

In the figures, the side and back walls of the box are designated by the numerals 4 and 5 respectively and the lid by the numeral 6.

The device of the present invention comprises essentially an angular sheet of metal or other suitable rigid or stiff material 7 having the upwardly extending arm 8 and the horizontally projecting arm 9. The horizontal arm preferably tapers downwardly as illustrated best in Fig. 1. The lower portion of the horizontal arm is flanged outwardly and then down to provide the portion 10, which, as shown in Fig. 2, is adapted to lie against the outer surface of the end wall of the box. The lower edge of the portion 10 in turn is provided with teeth or prongs 11 adapted to engage and bite into the material of the end of the box.

Pivoted to the central or angular portion of the plate 7 is a clamping device 12. This comprises preferably a sheet metal member 85 having the flat portion 13 adapted to engage the upper portion of the inner surface of the end wall of the box, and the device 12 is so bent or formed that it may overlie the portions 9 and 10 of the plate 7, as illustrated 90 in Fig. 2, wherein it will be seen that the plate 12 has the flat portion 14 which overlies and engages the portion 10. The plate 12 is pivoted to the plate 7 at the point 15. A finger piece 16 on the end of the member 12 facilitates its manipulation.

From the foregoing, it will be observed that, in order to apply the plate 7 to the box, the portion 10 thereof may be pressed firmly against the upper outer surface of the end of the box, whereupon the member 12 may be turned down into locking position. Thereupon the plate 13, by engaging the inner surface of the box, will cause the prongs 11 of the plate 10 to be forced into the material of the box, thereby locking the member 7 securely in position.

From an examination of Fig. 1, it will be observed that the member 7 is provided with a downwardly extending arm 17. This

arm is formed at right angles to the arm 9, and is adapted to lie firmly against the back of the box. It will also be observed from an examination of Figs. 1 and 3 that the 5 arms 8 and 17 of the member 9 have the flanged portions 18 which lie against the back surface of the top of the box when the same is in open position. The arm 8 of the member 7 carries the plate 19 which is 10 adapted to lie against the surface of the front face of the lid when the same is open, and this plate 19 may also be used to support a display card 20. The lid of the box is grasped or engaged between the flange 18 15 and the plate 19, and is thus firmly secured to the arm 8 of the member 7. The lower portion of the rib 18 is preferably struck inward to provide a lug 21 which seats or engages against the bottom edge of the lid 20 to still further reinforce the connections between the parts.

From the foregoing description, it will appear that, after the device has been applied to the box, any attempt to turn the 25 lid back will be firmly resisted by reason of the engagement of the arm 17 against the back of the box, and by reason of the fact that the prongs 11 penetrate into the material of the end of the box.

30 While I have herein shown and described only a single form of construction embodying the features of my invention, still it will be apparent that many modifications may be made without departing from the spirit 35 thereof. Therefore, I do not limit myself to the details of construction herein shown and described, but include within the scope of my invention any equivalent construction operating in equivalent manners to produce 40 equivalent results.

I claim:

1. In a device of the class described, the combination with a plate having a member adapted to overlie the upper portion of the 45 outside of the box, said member being provided with wood-engaging teeth and having a third member adapted to engage the lid of the box, of a clamping device pivoted to said plate and having a bifurcated portion 50 adapted to engage the upper portion of the inside of the box and the first-mentioned member to thereby clamp said member

against the box and to force the teeth of said member into the material of the box, substantially as described. 55

2. In a lid-clamping device, the combination with a plate having three arms adapted to engage the upper edge of one end of the box, the lid of the box and the rear of the box respectively, the first-mentioned arm 60 being provided with a downwardly depending member having a plurality of teeth adapted to engage the outer surface of the upper portion of the box end, of a clamping member hinged to said plate and having a 65 bifurcated portion adapted to clamp the downwardly depending member into engagement with the upper portion of the box end, substantially as described.

3. In a lid-holding device, the combination with a plate having three arms adapted to engage the upper edge of the end of a box, the lid of the box and the back of the box respectively, the last-mentioned arms lying substantially in alinement with each 75 other and the first-mentioned arm being provided with a downwardly depending member having its inner surface of ragged formation to engage and grip the upper portion of the outside face of the box end, of a bifurcated member pivoted to the plate and adapted to clamp the downwardly depending member into solid engagement with the box end when the bifurcated member is forced down, substantially as described. 80

4. In a lid-supporting device, the combination with a plate having three arms adapted to engage the upper edge of the box end, the lid of the box and the back of the box respectively, of a lug carried by the last- 90 mentioned arm and adapted to engage and support the lower edge of the lid when the same is raised, there being a downwardly depending member on the first-mentioned arm and a bifurcated member pivoted to the 95 plate and adapted to clamp the plate and the box end solidly into engagement with each other when the bifurcated member is forced down, substantially as described.

EDWARD E. BRIGHT.
